GARMENT STRETCHER

Arthur C. Jack, Pittsburgh, Pa.

Application March 10, 1934, Serial No. 714,973

8 Claims. (Cl. 223—19)

My invention relates to a garment stretcher; that is, to a form for supporting garments which, having been cleansed in liquid, are to be dried. I have developed apparatus particularly adapted for drying women's suits of crocheted or knitted fabric, and the invention will be described as it is embodied in such apparatus.

It will be understood that apparatus of this general nature is broadly old, and that my invention lies in specific elaborations and refinements in structure. I have in mind the provision of apparatus which is readily adjustable to accommodate all the variations in dimensions in which garments for different persons vary. There are independent adjustments for variations in size of arms and bodice; the apparatus may be adjusted for bodices of different lengths, for bodices of different widths at the top, and different widths at the bottom, for different arm lengths and arm widths, and for skirts of various lengths, waist lines, and bottom widths. Conveniently, the apparatus comprises two independent portions—an upper portion and a lower. The upper portion of the apparatus is constructed in halves which are relatively swingable about a vertical axis, to facilitate the assembling of a coat, or a closed bodiced sweater or jacket thereupon. It is characteristic of the apparatus that all elements thereof normally extend in common plane, there being no protruding parts of such nature as tend to produce bulges in the garments stretched and dried thereon. It is additionally characteristic of my apparatus that the garments may be held in place thereon by means of snap-clothespins, thumb-tacks, or basting; and certain elements of the apparatus are adapted to project below the garment secured thereon, to provide legs upon which the apparatus may stand while the garments are drying.

In the accompanying drawing Fig. I is a view in front elevation of the upper body portion of the apparatus; Fig. II is a view of the same in elevation from above; Fig. III is a view in plan of a set of interchangeable elements for the upper body portion of the apparatus; Fig. IV is an isometric view of a pair of such interchangeable elements, indicating how they are assembled face-to-face for service in the apparatus; Fig. V is a view partly in side elevation and partly in vertical section of a specialized fastener employed in the apparatus; Fig. VI is a view in front elevation of the lower portion of the apparatus; Fig. VII is a fragmentary view, comparable to Fig. VI, illustrating a mod-

ification; Fig. VIII is a view to larger scale, illustrating in cross section the structure of the apparatus on the plane VIII—VIII of Fig. I; Fig. IX similarly illustrates the structure on the plane IX—IX of Fig. I; and Fig. X shows, to different scale, the structure as it appears on the plane X—X of Fig. I.

Considering first the upper portion of the apparatus—the portion upon which coats, jackets, or sweaters are dried—it will be noted that a central structure 1 is provided. This central structure comprises two members 1a and 1b which are swingably connected adjacent their top and bottom ends by means of hinges 2. The central member 1a carries the elements which comprise one half of the structure, and the member 1b carries the elements which comprise the other half, and as so carried upon the two hinged central members 1a, 1b, the two halves of the structure are relatively swingable from a spread position, in which the halves lie in common plane (see full lines in Fig. II), to a position of coincidence (see dotted lines in Fig. II which indicate the halves approaching such position of coincidence). The value of this feature will be later described.

The elements carried by each of members 1a, 1b comprise companion arm members 3 and 4, a side member 5, and a cross member 6. The arm member 3 is, at its inner end, secured in morticed joint to the upper end of central member 1a; at its outer end the arm member 4 is pivotally connected to the member 3, and at its inner end is adjustably secured to the central member 1a, by means of a screw fastener 7. A screw fastener 8 adjustably secures the upper end of the side member 5 to the arm member 4, and fasteners 9 and 10 adjustably secure the opposite ends of the cross member 6 to the members 1a, and 5, respectively. Inasmuch as the two halves of the structure are identical in this case, I have applied in each half the same reference numerals to indicate identical parts.

To the ends in view the union of the outer terminals of arm members 3 and 4 is particularly effective. As indicated in Fig. I, the arm members 3, 4 incline from spaced relation at their inner ends into contact at their outer ends. The outer end of arm member 3 is chamfered or curved at 11, and rests with rocking engagement upon the upper edge of arm member 4. The pivotal union of the outer ends of arms 3, 4 is effected by means of a disk 13, Fig. VIII. Opposed recesses 12 and 14 are formed in the arm members 3 and 4, and in

these recesses the disk 13 is located—approximately one-half of the disk being located in each recess. The disk is rigidly secured, by means of rivets 15, to the lower arm member 4, and is pivotally secured to the upper member 3 by a pin 16. Thus, it will be understood that the arm member 4, in being vertically adjustable at its inner end, may be angularly shifted relatively to the member 3. Accordingly, adjustment may be made for variations in sleeve width of the garments to be treated.

The adjustable union of the inner end of the arm member 4 with the central member 1a, the union of the side member 5 with arm member 4, and that of the cross member 6 with each of the members 5 and 1a are of common nature, insofar as they all admit of adjustment, and all cooperate in permitting the members 1a, 3, 4, 5, and 6 to extend in common plane. A minute consideration of the union of side member 5 with arm member 4 will serve generally for all the adjustable unions mentioned immediately above.

The arm member 4 is provided with an elongate recess, or two-sided groove 17, and the upper end of the member 5 is morticed to provide a terminal tongue 18 (Fig. IX) which lies in the groove. The proportions are such that the member 5 is flush with the member 4. A slot 19 is formed in the recessed body of the arm 4, and the fastener 8, extending through the tongue and slot, holds the parts in such position.

As shown in Fig. V, the fastener comprises an internally threaded tube 20 having a thin, flat head 21, and a threaded shank 22 which in service extends into the tube 20. The screw shank 22 has a thin, kerfed head 23, whereby a screw driver, a coin, or other convenient instrumentality may be employed to adjust the screw in the tube. Fig. IX illustrates the position of the screw fastener in service. It will be observed that the tube 20 projects through the slot 19 and into the tongue 18 of member 5; the two heads 21 and 23 lie against the opposite outer faces of the arm 4 and tongue 18, respectively; the tube 20 is shorter than the aggregate depth of the slot 19 and tongue 18, whereby the screw 22 may be run in, and the tongue 18 and arm 4 clamped in secure position between the heads. Upon loosening the screw fastener, the upper end of side member 5 may be adjusted longitudinally of the arm member 4, i. e. the member 5 may be adjusted laterally of the central member 1a. The opposite ends of the cross member 6 may in such manner be adjusted longitudinally of the members 1a and 5, and the inner end of arm 4 may be adjusted longitudinally of the member 1a.

I have referred to the member 6 as a cross member; as a matter of fact the member 6 comprises two complementary elements 6a and 6b, to the end that the effective length of the member (elements 6a, 6b) may be varied. Advantageously, the members 6a, 6b are identical, each comprising a flat, round-ended body having a terminal orifice 6c (Fig. IV), an elongate slot 6d extending parallel to and offset from the longitudinal axis of the member, and a side orifice 6e located adjacent one end of the slot and offset on the opposite side of said axis an interval equal to the interval of offset of the slot. The duplicate structure of the elements 6a, 6b is important, in that it permits one machine

set-up to be used in production. In assembly, the two identical elements 6a, 6b are reversed, so that the side orifice 6e of element 6a overlies and registers with the slot 6d in the element 6b, and the orifice 6e of element 6b registers with the slot in the element 6a. A screw fastener 24 (Fig. X) is installed in each orifice 6e, and projects through the slot 6d in registry therewith. It will be understood that one fastener 24 is immovably stationed (in orifice 6e) in each of the elements 6a, 6b, but, due to the slots 6d, the two elements may be relatively adjusted axially, when the screw fasteners are loosened. This organization affords a very strong union of the two elements 6a, 6b when the fasteners are tightened, and affords means for readily varying the effective length of the two elements. Due to the particular organization described, there is no possibility of the elements shifting out of alignment, nor of the fasteners, when loosened, from sliding along the slots 6d and becoming disarranged. In such organization, the opposite, outer ends of the elements extend from the assembly, whereby the fasteners 9, 10 may be projected through the orifices 6c, to secure the elements to the members 1a and 5 (cf. Figs. I and X). It will be observed that the member 1a is grooved in the front (17a) and the side member 5 is grooved in the back (17b) to admit of assembly in common plane (cf. Fig. X).

Preparatory to using the apparatus, the fasteners 7 are loosened and each of the members 4 is swung to the position in which the interval from the bottom edge of such member (4) to the top edge of the companion member 3 substantially equals the sleeve width of the garment to be dried. Then the screws 7 are tightened. Next, the upper ends of the side members 5 are adjusted longitudinally of the arm members 4, whereby the equivalent chest or bust dimension of the garment is provided in the frame. The cross members 6 are adjusted vertically of the members 1 and 5, so that such members 6 will lie within and even with the bottom of the garment placed on the apparatus. And then the lengths of cross members 6 are adjusted in the manner already explained, to regulate the bottom width of the side members for the bottom of the garment. Then, the garment is placed on the frame, as the dotted lines G indicate; the garment is stretched taut, and snap-clothespins of well-known structure are secured upon the garment along the edges of the frame. The clothes-pins are used on the arms 3, 4 to hold the ends of the sleeves in place; clothes-pins are employed along cross members 6, to hold the bodice of the garment taut on the frame; indeed the clothes-pins are readily installed wherever needed to keep the garment evenly stretched and taut on the frame.

The particular hinged structure of the apparatus is exceedingly valuable in simplifying the assembly of the garment thereupon. The halves of the frame are swung upon the hinges 2, and brought almost to coincidence, as indicated in Fig. II. The relative positions of the frame halves make it an easy matter to slip the sleeves of the garment upon the arm members 3, 4 and then to slip the bodice of the garment down and over the body members 1, 5 of the frame. Then the frame halves are swung open and the garment is stretched, ready for such minute adjustment as is accomplished by the use of clothespins. Hence, the ordinarily difficult task of

pulling the garment into place upon the frame is greatly facilitated.

While it is possible to construct the apparatus of metal, in the best interests of economy and 5 utility I have particularly adapted it for construction of wood, say of maple. Accordingly, in cases where the particular fabric of the garment will permit, it is possible to employ thumb tacks, instead of clothes-pins to secure the garment upon the frame. I also contemplate basting (rough stitching) the garment in place upon the frame.

In cases in which there is great variation in the sizes of the garments being treated, say in 15 a commercial dry-cleaning establishment, one set of cross members 6 may not afford a sufficient range of adjustment of the apparatus. In such event, I supply several auxiliary sets of elements which may be interchanged with the cross members 6. The two cross members 6, as mentioned, comprise four elements (6a, 6b, 6a, 6b; Fig. X), and with each apparatus, I ordinarily supply three sets of elements 6a, 6a' and 6a''. Fig. III illus. rates one element of each set, there 25 being, of course, four elements in each set. So, it will be understood that the interchangeable elements 6a, 6a', 6a'' admit of great range of adjustment in my apparatus.

The lower portion of the apparatus is designed 30 in this case for the stretching and drying of skirts, and comprises two side members 26 united at their upper ends by a cross member 27, and adjacent their lower ends by a cross member 28. The cross members 27 and 28 are each constructed, 35 whereby the interval between the tops of the side members 26 may be varied for different sizes of waist line in the skirts being dried, and the interval between the lower ends of the side members may be regulated for variations in 40 skirt flare or bottom dimension. The side members are each grooved at 29 and 30, to receive the ends of the compound cross members, in the manner already described in connection with 45 the side members 5 and cross members 6, and the lower of the cross members—member 28—is vertically adjustable on the side members 26. A slot 31 in each side member admits of such adjustment. Alternately, the side members 26 may 50 be provided with a series of holes 32 in close juxtaposition, and the fasteners 33 may be withdrawn to admit of movement of the cross member 28. Upon selection of appropriate holes 32, and the securing therin of the fasteners 33, the 55 cross member 28 may be secured in desired position longitudinally of the members 26. (In like fashion a series of holes 32 may be employed in place of the slots 19 in the upper portion of the apparatus.)

60 In service the cross member 27 is adjusted in length so that the waist of the skirt assembled upon the form is drawn taut and flat across the side members. The cross member 28 is adjusted vertically on the side members to 65 such position that the bottom hem of the skirt is about even with the bottom edge of such cross member; the cross member is also adjusted as to length, so that the bottom of the skirt is held taut, and the inclination of the side members 26 corresponds to the flare of the skirt. Clothespins are used to secure the waist band of the skirt to the cross member 27, and such pins are also installed at intervals to secure the bottom of the skirt to the cross member 70 28. Manifestly, the skirt may be drawn taut

vertically of the frame and held so by the clothes-pins, while the initial adjustment of the frame is so determined that the skirt is taut transversely of the frame.

In both the upper and lower portions of the apparatus the side edges, over which the garments are drawn, are round as indicated at 34 in Figs. VIII, IX, and X, so there will be no objectionable wrinkles or creases in the dried garment. As mentioned in the case of the cross members 6 in Fig. I, one or more sets of auxiliary elements may be provided as substitutes for the cross member 27; that is, if the range of waist adjustment for the garments is insufficient in the single pair of elements forming the cross member, auxiliary sets may be provided with each apparatus.

Another feature of the apparatus merits observation. In both the upper and lower portions of the apparatus, the side members extend 85 below the garment assembled thereon, providing legs upon which the frame may be stood, leaning against a wall or other support.

I claim as my invention:

1. A garment stretcher formed substantially 100 of wood, said garment stretcher comprising two side members, and two spaced-apart cross members extending between said side members, means for severally adjusting the lengths of said cross members, each cross member including at its opposite ends a terminal tongue of less thickness than the thickness of the cross member, each of said side members being grooved to receive the terminal tongues of said cross members, whereby the side members and 105 cross members lie in substantially common plane, a passage through each tongue of said cross members and passages in said side members for severally registering with the passages in said tongues, and screw fasteners severally 110 extending through the registering passages in the tongues and side members for pivotally uniting the members, said screw fasteners each having opposite low heads lying substantially 115 flush with the opposite faces of said assembled 120 members.

2. The structure of claim 1, in which each cross member comprises elements relatively 125 movable for adjusting the length of the cross member, and having screw fasteners of said structure for securing the relatively movable elements in adjusted positions.

3. The structure of claim 1, in which each of said side members includes means for receiving a screw fastener, said means extending 130 longitudinally of said tongue-receiving groove in the side member, whereby said cross members may be relatively adjusted longitudinally of said side members.

4. In a garment stretcher, the combination of 135 a vertical central member, a pair of arm members extending oppositely from the sides of said central member, each pair of arm members comprising an upper and a lower member which converge outward from said central member and 140 are interconnected adjacent their outer ends, means for adjustably securing the inner end of each lower arm member to said central member, whereby the inner ends of such lower arm members are adjustable longitudinally of said central 145 member, a side member on each side of said central member and being spaced an interval therefrom, said side members being severally pivotally secured to said lower arm members intermediate their ends, means whereby the up- 150

per ends of said side members may be adjusted longitudinally of said lower arm members, and adjustable cross members spaced an interval below said lower arm members and connecting said central member with said side members.

5. The structure of claim 4, in which said cross members comprise two sets of relatively adjustable elements, one set extending from each side member to said central member, and
10 means for adjusting each of said sets of elements longitudinally of said central member and side member associated therewith, whereby the two sets of elements which comprise the cross members are severally adjustable in length
15 and vertically of the central and side members.

6. In a garment stretcher, the combination of two vertical central members hinged together to swing about a vertical axis, a pair of arm members extending laterally from each central member, each pair of arm members comprising an upper and a lower member, means for slideably securing the inner end of each lower arm member to its associated central member, a side member spaced an interval laterally from each
20 central member, pivotal means for slideably securing each side member to one of said lower arm members intermediate the opposite ends of the last-named member, and a cross member interconnecting each central member and side
25 member an interval below the lower arm member connected thereto, said cross members being ad-

justable in length, and means for slideably securing the cross members to the central and side members respectively.

7. In a garment stretcher substantially constructed of wood, including two opposed sets of arm members, a side member extending downward from each set of arm members, and adjustable cross members extending between said side members, the combination of means for slideably securing one of said members to another, said securing means comprising a tongue extending from, and of reduced thickness relatively to, one of the members, an elongate groove formed in an associated member for slidably receiving said tongue, a second elongate groove formed in the last-mentioned member, said second groove extending in length with said first-mentioned groove and extending in depth transversely of the first-mentioned groove, and a fastener projecting through said tongue and said
90 second groove.

8. In a garment stretcher or form, an adjustable member comprising two complementary elements each including a slot, and an orifice offset from the slot, the orifice of one element registering with the slot of the other, and a fastener extending through each set of registering slots and orifices, whereby said fasteners are secured against lateral displacement and said elements are relatively adjustable.
